LEWIS C. BROECKER, OF AKRON, OHIO, ASSIGNOR TO THE FIRESTONE STEEL PRODUCTS COMPANY, OF AKRON, OHIO, A CORPORATION OF OHIO

VALVE-MAKING MACHINE

Application filed August 7, 1928. Serial No. 298,108.

This invention relates to apparatus for manufacturing tire valve stems and has particular reference to automatic machines for punching a valve seat, shearing a flat side on the stem and stamping a name on the flat side.

The object of the invention is to devise a machine for effectively and efficiently carrying out the above operations without the intervention of a human agency.

The foregoing and other objects are obtained by the device illustrated in the accompanying drawings and described below. It is to be understood that the device is not limited to the specific form thereof disclosed herein.

Of the accompanying drawings,

Figure 1 is a front elevation of a machine embodying the principles of the invention;

20 Figure 2 is a side elevation thereof;

Figure 3 is an enlarged scale detailed plan of the table portion of the apparatus;

Figure 4 is an enlarged scale front elevation thereof;

25 Figure 5 is an enlarged scale side elevation thereof;

Figure 6 is a still further enlarged scale vertical sectional detail of the valve seat upsetting operation;

30 Figure 7 is a vertical sectional detail of the valve stem shearing operation;

Figure 8 is a plan detail of the stamping operation;

Figure 9 is an end elevational detail there-
35 of; and

Figure 10 is a side elevational detail of the shearing mechanism during the positioning of the valve stem.

Referring to the drawings, the numeral 10
40 denotes the frame of a punch press on which the valve making machine is supported. Upon the upper portion of the frame is mounted a vertical track 11 in which is adapted to reciprocate a crosshead 12 oper-
45 ated by crank 13 which is rotated by motor 14 through suitable reduction gears. Projecting from the lower end of crosshead 12 is a vertical shaft 15 carrying a bracket 16 to be reciprocated by the crosshead. One side
50 of the bracket carries an arcuately disposed

series of devices, namely, an air jet 17, a depth-sounding tool 18, seat upsetting punches 19 and 20, and a final seat-shaping punch 21. The other side of the bracket carries an elongated shearing punch 22 and 55 an air jet 23.

A table 24 supported on frame 10 vertically below crosshead 12 carries thereon an indexing wheel 25 having a series of equidistantly spaced notches about its outer periphery. The wheel 25 preferably carries a correspondingly notched hardened steel plate 26 about its upper rim for supporting the base flanges 27 of valve stems 28 placed in the notches 29 of the indexing wheel. As 60 wheel 25 is rotated the valve stems are maintained in the notches by means of a guard band 30. An arcuate bracket 31 is formed with a series of apertures 32 having hardened bushings 33 provided therein for respectively 65 aligning the devices 18, 19, 20 and 21 with valve stems carried in notches 29 of the indexing wheel. A spring-pressed finger 34 is attached to bracket 31 for ejecting each valve stem from its notch as it passes from the 70 punching operation.

The indexing wheel is periodically rotated through an arc equal to the distance between the notches by means of an arm 35 reciprocated by cam 36 mounted on shaft 37 and rotated from the shaft of crank 13 through bevelled gears 38. One end of arm 35 is forcibly held against cam 36 by spring-pressed block 39 and the other end of the arm is provided with a pin 40 engageable successively 75 in notches 29 and yieldingly held therein by spring 41. The degree of angular movement of the indexing wheel is adjustably regulated by means of a screw 42 engageable with a pin 43 carried on arm 35. Pin 40 is maintained 80 in notch 29 during the forward movement of arm 35 to rotate wheel 25 in the direction shown in the arrow in Figure 3. Upon the backward movement of arm 35 the wheel is held against rotation by the punches which 85 are then in their downward position and the end of the arm carrying pin 40 is moved radially away from wheel 25 in order to disengage pin 40 from the notch 29, this movement being effected by a lever 44 operated by 90 95 100

lever 45 which is engaged by arm 46 in turn oscillated by connecting rod 47 which is reciprocated by crank 48 affixed to shaft 37. Arm 35 is guided and aligned by means of a 5 guide block 49.

Positioned on table 10 vertically below shearing punch 22 is a support 50 carrying a pair of shear plates 51 cooperating with punch 22 to shear a flat side on the valve 10 stems. The latter are properly positioned on plates 51 after dropping from the indexing wheel, by means of a reciprocable forked member 52 sliding across plates 51 and engageable with the base flange 27 of the valve 15 stem as shown in detail in Figure 10. After the valve stem is positioned on plates 51 with its base flange in abutment with a stop 53 and before shear punch 22 descends, member 52 is retracted; this member being actuated 20 by arm 46 reciprocated by connecting rod 47 as mentioned above.

Chips formed by the punching operation are blown from the apparatus by means of air jet 23 connected to air valve 54 by means 25 of flexible hose 55 and whose operation is timed by cam 56 affixed to shaft 37. A pair of oppositely rotatable circular dies 57 and 58 are mounted below the shearing mechanism and are adapted to engage the valve 30 stem that has been forced through shear plates 51 into a guide block 59 and between dies 57 and 58. The latter are rotated from shaft 37 through gears 60, 61, 62, 63 and 64 and are timed so that letters or numbers 65 35 embossed on the dies will pass across the flat surface of the valve stem, stamping the same and ejecting the stem from the apparatus.

Depth-sounding tool 18 is reciprocably mounted in bracket 16 and yieldingly held in 40 its downward position. It serves as a safety device and in the event that the bore of valve stem 28 is not deeply enough drilled, depth-sounding tool 18 will be forced upwardly with respect to bracket 16 and will operate 45 electrical contact switch 66 to close a circuit and energize solenoid 67 releasing a spring-pressed latch 68 for operating clutch rod 69 to stop the operation of the machine. Thus punch 19 is safeguarded against damage by 50 being forced into a valve stem which has been accidentally given too shallow a bore. Furthermore, any obstruction in the bore will operate tool 18 to stop the machine. A hand lever 70 mounted on the front portion of table 55 24 is also adapted to operate suitable contacts for energizing the solenoid to stop the machine, only a slight touch by the operator being necessary to actuate lever 70. An inclined trough-like guide 71 serves as a gravity conveyor for feeding valve stems to the indexing wheel and also serves as a means for holding a number of valve stems in reserve to be operated upon by the machine. This 60 guide has been removed from Figures 1 and 65 4 in order not to obscure the construction of

the mechanism appearing behind the same.

In the operation of the machine a number of partly finished valve stems formed with external threads and with a bore having a shoulder adjacent one end thereof, are placed 70 in guide 71 and are automatically successively positioned in notches 29 as the index wheel is periodically rotated. As a valve stem comes into position under air jet 17, crosshead 12 descends and forces bracket 16 downwardly 75 to seal air jet 17 against the base flange of the valve stem and a blast of air is forced through the bore of the valve stem to blow out any chips that may have lodged therein. As wheel 26 is again indexed the valve stem is brought beneath depth-sounding tool 18 which is then inserted into the bore to test 80 the depth of the shoulder. If the depth of the bore to the shoulder is too shallow or is obstructed, tool 18 will trip electrical contacts 85 66 to stop the machine, but if the bore is of sufficient depth the operation continues. Upon the next indexing operation the valve stem is brought under punch 19 which is then forced downwardly to partially upset a seat 90 in the bore of the valve stem. After punch 19 is retracted by the upward movement of the crosshead the wheel is again indexed and punch 20 is forced into the bore of the stem to further upset the seat. The operation of 95 forming the seat is best illustrated in Figure 6 of the drawings. Then wheel 26 is again indexed and the next stroke of bracket 16 forces punch 21 into the bore for the final 100 forming operation of the valve seat. It will be understood that a valve stem is placed in each notch as the wheel is rotated and that therefore all of the above operations are simultaneously performed on successive valve stems.

As each of the stems comes into contact 105 with spring-pressed finger 34 it is ejected from notch 29 and falls onto plates 51 whereupon it is carried across these plates by forked member 52 until the base flange drops over the end of the plate when member 52 will be retracted and shear punch 22 will descend and force the valve stem through plates 50 shearing off a flat surface on each side of the valve stem and forcing the stem downwardly between and into engagement with circular dies 57 and 58. As the dies rotate and stamp 110 a name, number or other indicia upon the flat side of the valve stem the latter is projected from the machine and drops into a suitable 115 container (not shown).

Modifications of the invention may be resorted to without departing from the spirit thereof or the scope of the appended claims.

What is claimed is:

1. In a valve making machine, a rotatable indexing wheel formed with a series of equally spaced notches about its outer periphery, means for intermittently rotating said wheel through a distance equal to the space be- 120 125 130

- tween said notches, means for feeding a series of valve stems successively into said notches as said wheel is rotated, a series of tools adapted to perform successive operations upon the series of valve stems, said tools being positioned to be aligned with successive valve stems as said wheel is rotated, a shearing punch and a pair of shear plates cooperating to form a flat side on said valve stems, 5 means for successively removing the valve stems from said indexing wheel and positioning same upon said shear plates, and a pair of rotatable stamping dies mounted below said plates for stamping indicia upon the 10 flat side of a valve stem after the latter is forced through the shear plates by the shearing punch.
2. In a valve making machine, the combination of a pair of shear plates, means for successively feeding and positioning valve stems on said shear plates, a reciprocable shearing punch for forcing said valve stems through the shear plates to form flattened sides on the valve stems, and a pair of rotatable stamping dies positioned below said shear plates and adapted successively to engage the flattened sides of the valve stems as the latter are forced through the plate by the shearing punch.
3. In a machine for making valve stems, a reciprocable punch for engaging a shoulder formed in the bore of said valve stems for upsetting the metal thereof to form a valve seat, and a safety device for stopping said machine if the bore of said valve stem is too small or too shallow, said safety device including a spring-pressed rod adapted to be inserted in the bore of said valve stem in advance of the punching operation and electrical means 20 for stopping the machine if the rod does not project to a sufficient depth within the bore.
4. A valve stem finishing machine comprising in combination, means for successively cleaning the bores of a series of valve stems, 25 means for testing the depth of the bore of each valve stem, means for upsetting a valve seat within said bore, means for forming a flat side on the exterior of said valve stem, means for stamping indicia upon said flat side, means for conveying the valve stems into successive operative positions for the operation of each of the above-mentioned means, and means for simultaneously operating each of the above-mentioned means.
5. A valve stem finishing machine comprising in combination, means for successively cleaning the bores of a series of valve stems, means for upsetting a valve seat within said 30 bore, means for forming a flat side on the exterior of said valve stem, means for stamping indicia upon said flat side, means for conveying the valve stems into successive operative positions for the operation of each of the above-mentioned means, and means for simultaneously operating each of the above-mentioned means.
6. In a machine for making valve stems, a reciprocable punch for engaging a shoulder formed in the bore of said valve stems for upsetting the metal thereof to form a valve seat, and a depth testing device for stopping said machine if the bore of said stem is too small or is obstructed or if the shoulder in the bore is not of sufficient depth.
7. A valve stem finishing machine comprising in combination, means for testing the depth of the bore of a series of valve stems fed into said machine, means for upsetting a valve seat within said bore, means for forming a flat side on the exterior of said valve stem, means for stamping indicia upon said flat side, means for conveying the valve stems into successive operative positions for the operation of each of the above-mentioned means, and means for simultaneously operating each of the above-mentioned means.
8. A valve stem finishing machine comprising in combination, means for upsetting a valve seat within the bore of a series of valve stems fed into the machine, means for forming a flat side on the exterior of said valve stem, means for stamping indicia upon said flat side, means for conveying the valve stems into successive operative positions for the operation of each of the above-mentioned means, and means for simultaneously operating each of the above-mentioned means.
- In witness whereof I have hereunto affixed my signature this 16th day of July, 1928.
- LEWIS C. BROECKER.
